UNITED STATES PATENT OFFICE.

WORCESTER HADDOCK, OF CINCINNATI, OHIO.

CABLE-RAILWAY-CONDUIT CONSTRUCTION.

SPECIFICATION forming part of Letters Patent No. 399,145, dated March 5, 1889.

Application filed June 22, 1888. Serial No. 277,914. (No model.)

To all whom it may concern:

Be it known that I, WORCESTER HADDOCK, a citizen of the United States, and a resident of Cincinnati, in Hamilton county and State 5 of Ohio, have invented certain new and useful Improvements in Cable-Railway-Conduit Construction, of which the following is a specification.

The object of my invention is to provide a 10 durable construction for the conduits of cable railways which is at once cheap of manufacture, quickly placed into working position, easily repaired, and efficient in use. I may dispense with the use of concrete when de- 15 sired. My construction may be placed upon truss-work, and, when necessary, filled in afterward, and be as efficient in use as if placed underground.

In the accompanying drawings, forming 20 part of this specification, Figure 1 is a side view of the yoke and accompanying parts and of one of the gusset-plates used in connection with the man-holes, the tram-rails, slot-rails, and side, bottom, and top plates of the 25 conduit being shown in section. Fig. 2 is a top view showing the man-hole construction or opening. Fig. 3 is a side view of a section of the conduit where a man-hole or opening is present, also showing the sewer-connection 30 from the conduit, part of the bottom plate being broken away. Fig. 4 is an end view of the side and bottom plates of the conduit, the side plates being shown with strengthening-ribs. Fig. 5 is a side view of a modification 35 of the strengthening-ribs in position, two side plates being used; and Fig. 6 is a front view of said modified form of strengthening-rib. Fig. 7 is an enlarged view of part of the 40 yoke and bottom plate, showing the locking-lug on said yoke. Fig. 8 is a view of one of the ribbed side plates shown in Fig. 4.

The yoke is represented by the letter A, B representing the struts, C the tie-bar, D the bottom plate of the conduit, E the side plates 45 of the conduit, and F the top plates. I preferably construct the yokes substantially of the form shown, the lugs G being cast on each wing of the yoke as a convenient point of connection for the strips B. Near the top 50 of the yoke I provide the slots a a' and the extension a^2 . (See Fig. 1.) Through the extensions a^2 , I pass a bolt, a^3 . I also provide a

bolt, a^4 , which passes from the slot a to the top of the yoke, the said slot a being present to facilitate the placing of said bolt a^4 into position. These bolts a^3 and a^4 hold the tie-bars C in position. At that part of the yoke A on which the bottom plates, D, rest I provide the flanges a^5 , one on each side of the yoke, thus forming a better and broader bearing- 60 surface for said bottom plates, D. These bottom plates, D, are semicircular in shape, but may be of any other shape, or may be made in two parts. In each end of said bottom plates, D, are cut the recesses b . On that 65 part of the yokes A on which the bottom plates, D, rest I provide the lugs b' , one-half of which lugs fit into the recesses b in the bottom plates, thus locking said bottom plates when in position. 70

On the bottom of the side plates, E, I provide the feet or lugs b^2 , which feet rest on and fit over the top edges of the bottom plates, D, as shown in Figs. 1 and 4. These side plates, E, rest against the side flanges, H, on the yokes, 75 (see Fig. 1,) and are tightly secured in position at the bottom by driving the wedges d between the said side plates and the lugs J on the yokes, and at the top by driving the wedges d' into the slots a' . (See Figs. 1 and 3.) 80 These plates E may be secured in position in any other convenient manner, as may also the bottom plates. The top plates, F, are of the peculiar shape shown, and provided at the bottom with the bifurcated feet d^3 , which rest 85 and fit over the top edges of the side plates, E, holding the said plates tightly in position, and as the top portions of the said top plates rest against the slot-rails K when the earth is filled in on said top plates they are secured 90 in immovable position. These feet d^3 may be of any shape desired and are preferably continuous on the plates; but they may be placed at intervals on said plates. These bottom, side, and top plates are used in sections extending from one yoke to the other, and the side plates are preferably provided with strengthening-ribs, as g . 95

In Figs. 5 and 6 I have shown two side plates, E, each provided with a slot, g' , into which the hook-shaped arms g^2 of the modified form of strengthening-ribs L fit and lock. This form of strengthening-rib is of the peculiar shape shown, having the bifurcated foot-

piece g^3 , provided with a lug, g^4 , and at the top being bent inward to fit the top plates and having the web-shaped portion g^5 . When this form of strengthening-rib is used, I usually 5 cast a bracket, M, on the bottom plate, D, said bracket being provided with a recess, h , into which the lug g^4 of the strengthening-rib L fits and rests. I may use any other form of strengthening-rib desired. The slot-rail K is 10 of the peculiar shape shown, its upper half being thickened, as more strength is there needed, as the bolt h' passes through said portion. In the lower edge of the slot-rail is cut the recess m , into which the lip m' on the 15 auxiliary slot-rail clamp K' fits. This auxiliary slot-rail is preferably shaped as shown, having the thickened portion m^2 , on which the slot-rail K rests, as shown in Fig. 1. The slot-rail K is held in position by the bolt-connection h' , and the auxiliary slot-rail K' by the bolt-connection h^3 . This auxiliary slot-rail K' strengthens the slot-rail K and takes 20 a large amount of vertical strain off the bolt h' . 25 At suitable intervals along the line of the cable conduit I provide man-holes. I preferably construct them as follows: To the outside of two adjacent tie-bars C, I connect, by bolts n the peculiarly-shaped gusset-plates M'. 30 N represents a cross-bar T-headed at each end and bolted in position between said gusset-plates by the bolts n' . Two short bars, P, extend from the bar N to the slot-rail, and are each provided at both ends with the L-shaped 35 heads p , and said short bars P are connected to the slot-rail and to the bar N by the bolts n^3 . The inner faces of the short bars P are rabbeted at t , as is also the long bar N between said short bars P. 40 R represents the pocket or opening of the man-hole, provided at the top with the flange t' , (see Fig. 1,) which rests on and fits against the ledge t^2 on the bottom of the bar N. (See Figs. 1 and 2.) The pocket or opening R is 45 cast onto one of the side plates, E. The cover R' fits the rabbeted edge on the bars N and P. The connection with the sewer is made as follows: To the bottom plate I preferably cast the short pipe R², having the double lug w , 50 which forms a T-shaped slot, w' , on each side of said pipe. The mouth w^3 of the sewer-pipe S is fitted over the short pipe R², and the collar w^2 passed over said sewer-pipe. A bolt, w^4 , is passed through the T-slots w' and through the

lugs on the collar w^2 , on the end of which is 55 screwed the nut w^5 , which bolt-connection connects the two pipes.

What I claim as new and of my invention, and desire to secure by patent, is—

1. In a cable-railway-conduit construction, 60 bottom plate, D, recessed at each end, in combination with lug b' on the yoke, substantially as set forth.

2. In a cable-railway-conduit construction, 65 side plates, as D, having feet b^2 , said plates suitably wedged into position, substantially as set forth.

3. In a cable-railway-conduit construction, 70 side plates, E, in combination with a rib, as L, substantially as set forth.

4. In a cable-railway-conduit construction, 75 yokes and bottom, side, and top plates, as set forth, in combination with lugs, as J, and suitable wedges, substantially as set forth.

5. In a cable-railway-conduit construction, 80 the combination, with suitable frame-work, substantially as set forth, of the man-hole pocket R, having a flange, t^2 , to rest on a ledge on the bar N, substantially as set forth.

6. In a cable-railway-conduit construction, 85 T-headed bar N, bolted to the gusset-plates M', and the cross-bars P, said bars having the rabbeted edge t , substantially as set forth.

7. In a cable-railway-conduit construction, 85 a side plate, as E, having cast with it a man-hole pocket, substantially as set forth.

8. In a cable-railway-conduit construction, 90 a short pipe, R², cast with the bottom plate of the conduit, in combination with lugs w , forming T-slots w' , bolts w^4 , collar w^2 , and sewer-pipe S, substantially as set forth.

9. In a cable-railway-conduit construction, 95 the combination, with yoke and bottom, side, and top plates, of lugs, as J, and suitable wedges, and wedges, as d' , substantially as set forth.

10. In a cable-railway-conduit construction, 100 a yoke having flanges, as J, substantially as set forth.

11. In a cable-railway-conduit construction, 100 side plates, substantially as set forth, suitably wedged into position, substantially as set forth.

WORCESTER HADDOCK.
